UNITED STATES PATENT OFFICE.

GUSTAVE E. VILLARET, OF NEW YORK, N. Y., ASSIGNOR TO WILLIAM R. NOE & SONS,
OF NEW YORK, N. Y., A CORPORATION OF NEW YORK.

DESIGN FOR A LAMP BASE OR SIMILAR ARTICLE.

Application filed November 14, 1923. Serial No. 7,765. Term of patent 7 years.

To all whom it may concern:

Be it known that I, GUSTAVE E. VILLARET, a citizen of the United States, and residing at New York, in the county of New York and State of New York, have invented a new, original, and ornamental Design for a Lamp Base or Similar Article, of which the following is a specification, reference being had to the accompanying drawing, forming part thereof.

Fig. 1 is a diagrammatic outline taken on the line 1—1 in Fig. 2.

Fig. 2 is a side elevation of a base embodying my new design.

Fig. 3 is one-half of a diagrammatic outline of the base, taken on the line 2—2 of Fig. 2 and looking in the direction of the arrow, it being understood that the other half is identical.

I claim:

The ornamental design for a lamp base or similar article, as shown.

GUSTAVE E. VILLARET.
